UNITED STATES PATENT OFFICE.

PER FREDRIK ALARIK LIEDBECK, OF STOCKHOLM, SWEDEN.

APPARATUS FOR EVAPORATING SOLVENTS FROM SMOKELESS POWDER.

SPECIFICATION forming part of Letters Patent No. 718,484, dated January 13, 1903.

Application filed June 1, 1899. Serial No. 719,035. (No model.)

To all whom it may concern:

Be it known that I, PER FREDRIK ALARIK LIEDBECK, engineer, a subject of the King of Sweden and Norway, and a resident of Stockholm, in the Kingdom of Sweden, have invented certain new and useful Improvements in Apparatus for Evaporating the Solvent in the Manufacture of Smokeless Powder, of which the following is a specification, reference being had therein to the accompanying drawings.

This invention relates to an apparatus to be employed in the manufacture in known manner of either homogeneous or progressive smokeless powder from solutions, and the special task to be performed by it is to produce the desired kind of powder by the evaporation of the solvent from the solution spread out in thin layers superposed on one another.

In the accompanying drawings such an apparatus is shown in Figure 1 in a vertical section on line *a b* of Fig. 2, and in Fig. 2 in a cross-section on line *c d* of Fig. 1.

The apparatus consists of an open drum *A*, adapted to be rotated at great velocity and here shown in a horizontal position, said drum being fixed to one end of a shaft *B*, journaled in a frame and arranged to be rotated

30 by some known means. The drum is inclosed in a casing *C D* surrounding the drum, and for easy taking apart and putting together being suitably made in two parts, of which the part *D* or the cover can be inserted in

35 the interior of the drum and by means of readily-detachable bolt fastenings or eccentrics secured tightly to the edge of the other part. The walls of the two parts of the casing are arranged for heating by steam, hot

40 water, or the like—for instance, by making them hollow, as shown in the drawings, and conducting the heating agent into the cavities by means of pipes *E* and *F*. The space within the casing is connected by a pipe *I* or the like

45 with an apparatus for the introduction of heated air. The evaporation may alternately take place in a vacuum, in which case the apparatus is connected by means of a pipe *G* with a condenser, from which the air is evacuated and from which the accumulated con-

densed matter can be removed in some manner or other.

The air by which the solvent is absorbed is conducted by a pipe *G* to an apparatus for the recovery of the solvent by condensation 55 or absorption. Into the space within the casing *C D*, either inside or outside of the cylindrical wall of drum *A*, is inserted, through an air-tight joint, a pipe *H*, which can be shifted to and fro along the drum and is provided 60 at the end with a suitable nozzle through which the solution introduced in said pipe is ejected at a suitable pressure onto the surface of the drum. The solution ejected forms rings or spirals on the surface of the drum, 65 and these form together a firm and uniform layer which, together with other superposed layers, forms a coarse. By the combined influence of spreading the solution out in extremely-thin layers, heating, and creating 70 air-circulation or a vacuum the solvent has time to evaporate completely from one layer before a fresh one is superposed. The coarse of powder formed or courses, if several different kinds are superposed on one another, 75 constitutes or constitute a firm cylinder which when cut open can be readily removed from the surface of the drum on detaching the cover *D*.

Having now described my invention, what 80 I claim as new, and desire to secure by Letters Patent, is—

1. In an apparatus for evaporating the solvent in the manufacture of smokeless powder, the combination with a closed casing 85 having hollow walls arranged to be heated by steam or the like, of a cylindrical drum having its axis in a horizontal plane and rotating freely within said casing, and means for spreading out the solution on the said rotary 90 drum, substantially as described.

2. In an apparatus for evaporating the solvent in the manufacture of smokeless powder, the combination of the driving-shaft, the hollow cylindrical drum having one end 95 open and a closed wall secured to the said shaft, the casing, inclosing the said drum and having one wall extending into the drum and substantially concentric with the circular wall of the same, the outer and inner walls 100

of said casing being hollow and arranged to be heated by steam or the like, means for feeding the solvent to the said drum, and the air inlet and outlet pipes leading to and from 5 the said casing, substantially as described.

3. In combination, the driving-shaft, the hollow cylindrical drum having one end open and having an end wall provided with an inwardly-curving central portion, a two-part 10 casing having hollow walls concentric with the circular wall of the drum, said inner part of the casing having an inwardly-curving wall parallel with the end wall of the drum,

an air-inlet pipe connecting with the center of said casing-wall, and a delivery-pipe from 15 the upper part of the casing, and a pipe leading to the lower part of the casing within the wall of the drum for feeding the solvent, substantially as described.

In witness whereof I have hereunto signed 20 my name in the presence of two subscribing witnesses.

PER FREDRIK ALARIK LIEDBECK.
